COMBINED HAND SHIELD AND SLEEVE GUIDE FOR DRESSING CHILDREN

Floyd A. Jones, 1835 Molino Ave.,
Long Beach, Calif. 90803

Filed Oct. 31, 1966, Ser. No. 4,486

Term of patent 14 years

(Cl. D86—10)

Fig. 1

I claim:

The ornamental design for a combined hand shield and sleeve guide for dressing children, substantially as shown.
